GARMENT HANGER

James D. Coney, Chicago, Ill.

Application October 9, 1943, Serial No. 505,624

7 Claims. (Cl. 223—88)

This invention relates to garment hangers and more particularly to the combination wire frame and paper tube strut type garment hangers, although certain features thereof may be employed with equal advantage in connection with other types of garment hangers or for other purposes.

It contemplates more especially an improved garment hanger that embodies a combination wire frame and paper tube strut which can be readily assembled by the user to provide an improved hanger construction that is capable of sustaining heavy garments without the usual tendency of the wire hanger portion becoming separated from the paper tube strut.

One object of the present invention is to simplify and improve the construction of garment hangers embodying a combination wire frame and paper tube strut.

Another object is to provide an open wire garment frame for ready attachment to a paper tube strut without placing either element under tension, deformation or strain.

Still another object is to provide a garment hanger of the type mentioned having wire arms terminating in specially shaped open loop extremities to provide ready engagement with a paper tube strut without requiring either of the elements to be under tension, deformation or other strain in effecting the assembly thereof.

A further object is to provide an improved garment hanger constructed partially from non-metallic material to afford complete garment hanger utility with a combination wire and paper tube strut assembly.

A still further object is to provide a garment hanger of the type mentioned having wire arms terminating in open loops with stabilizing extensions to provide ready engagement with a paper tube strut without requiring either of the elements to be under tension, deformation or other strain in retaining the assembly thereof.

Still a further object is to provide a garment hanger of the type mentioned having wire arms terminating in open loop extremities with stabilizing fingers complementary to engaging notches in the paper tube strut to enable their assembly without placing either element under tension, deformation or other strain.

Other objects and advantages will appear from the following description of an illustrated embodiment of the present invention.

In the drawing:

Figure 1 is a front view in elevation of a gar-

ment hanger embodying features of the present invention.

Figure 2 is an end view in elevation of the garment hanger shown in Figure 1.

Figure 3 is a fragmentary sectional view in elevation of an end portion of the wire arm together with the complementary portion of the paper tube strut showing the assembled construction and relation of the garment hanger elements.

Figure 4 is a fragmentary sectional view in elevation of an end portion of the wire arm showing improved open looped extremities of the wire frame portion.

15 Figure 5 is a fragmentary end view in elevation of the end portion wire frame and paper tube strut assembled to receive a fastener to illustrate the manner of supporting a skirt or other garment therewith.

15 Figure 6 is a fragmentary front view in elevation of an end portion of the assembled wire frame and paper tube strut assembled to receive a fastener to illustrate the manner of supporting a skirt or other garment therewith.

25 Figure 7 is a fragmentary perspective view of one end of the paper strut showing the complementary features enabling assembly with the wire frame portion.

The structure selected for illustration is not intended to serve as a limitation upon the scope or teachings of the invention, but is merely illustrative thereof. There may be considerable variations and adaptations of all or part of the teachings depending upon the dictates of commercial practice.

The present embodiment comprises a wire or frame 10 of light gauge wire construction providing a double strand twisted shank 11 which terminates in a hook 12 of standard or suitable 40 shape and construction. The shank 11 extends downwardly in garment supporting arms 13 and 14 that diverge to provide the final angular configuration conforming to the suitable support of a garment such as a coat.

45 The diverging arms 13—14 of the frame 10 extend outwardly to merge in rounded ends 15 and 16 that are inwardly curved to present downwardly inclined and converging extensions 17 which are slightly curved in the direction opposite to the frame ends 15—16. Each of the downwardly converging extensions 17 terminate in outwardly extending open loops 18 and 19 comprising a part of the frame arms 13—14, respectively.

55 The downwardly extending frame loops 18—19

have an outwardly disposed leg 20 that is spaced from the downwardly extending frame arm extension 17 to terminate in a horizontally extending finger 21 that protrudes outwardly from each other to present a stabilizing influence on the frame strut to be hereinafter described. It should be noted that the outwardly extending open loop leg 20 extends upwardly at an inclined angle to present opposing engaging edges 22 and 23 substantially in horizontal alignment to frictionally fit in horizontal slots 24 provided in the bottom of a paper tube strut 25.

The paper tube strut 25 is preferably though not essentially convoluted from jute or other suitable materials to provide a rigid tubular cylindrical bar supported between the curved ends 15-16 of the frame 10 as will appear more fully hereinafter.

The length of the paper tube strut 25 is somewhat greater than the distance between the curved frame ends 15-16, since slots 26 are provided in the top portion of the paper tube strut 25 to communicate with both open ends 27 and 28 thereof to permit free registry with the curved ends 15-16 of the wire frame 10. This precludes the rotation of the paper tube strut 25 relative to the frame arms 13-14 and provides for the insertion of the downward converging frame arm extensions 17 so that the looped extremities 18-19 thereon will enter and protrude through the bottom slots 24 that are spaced from the ends 27-28 of the tube a distance corresponding with the spacing of the wire frame loops 18-19.

The looped frame extremities 18-19 are shaped and sized so that contact with the tube slots 24 is effected along a horizontal line to establish contact therewith as at 22-23, thereby preventing lateral movement of the wire arms 13-14 in either direction and maintaining the initial shape and diverging angularity thereof irrespective of the garment load thereon. With the frame arm terminal open loops 18-19 protruding through the bottom slots 24 in the paper tube strut 25, the outwardly extending loop fingers 21 rest on the interior bottom surface thereof to stabilize the assembled connection between the wire frame 10 and the paper tube strut 25. In spite of minute variations in the shape or configuration of the frame terminal loops 18-19 which may occur in large production operations, the open type loops 18-19 together with their stabilizing fingers 21 will permit sufficient yield to provide a perfect engaging fit with the bottom slots 24 of the paper tube 25.

It should be observed that this arrangement and method of assembly involves no tension, deformation or strain on either the wire frame 10, its arms 13-14, or its ends 15-16 or on the paper tube strut 25 as these elements are initially shaped, stamped and constructed to be perfectly complementary to each other so that they can be shipped knocked-down to save transportation space and thereafter readily assembled by the user without entailing any appreciable time, effort or inconvenience.

Any stresses or strains imparted to the garment frame 10 by virtue of the garment load thereon will not effect the assembled relation of the garment supporting elements. The assembled relation of the component elements is maintained owing to the fact that the inwardly curved frame arm ends 15-16 register with the paper tube strut slots 26 to prevent relative turning therebetween. Any tendency for inward or

outward displacement of the frame arms 13-14 relative to the tubular strut 25 is precluded by the looped extremities 18-19 which protrude in and through the bottom slots 24 of the strut 25 so that there is a horizontal line of contact between the extremities of the slot 24 and the extreme edges 21-22 of the looped extremities 18-19. This effects a dependable interengagement between the frame ends 15-16, on one hand, and the open, looped frame extremities 18-19, on the other hand, with the slots 26-24, respectively, in the tubular strut 25, thereby retaining the wire frame 10 and the tubular paper strut 25 in assembled relation without tension, deformation or strain on either or both other than the garment load thereon.

In order to support garments such as women's skirts from the frame 10 without doubling such garments over the tubular strut 25, any suitable fastener such as safety pins 29 extend through the loops 18-19 for engagement with the waistband of the skirt or other garment to effect the suspended support thereof. With these fasteners, such garments as skirts can be supported without folding or other undesirable creasing. This also permits the paper tubular strut 25 to be inserted between the frame ends 15-16 and their downwardly inclined and converging extensions 17 so that the enclosed looped extremities 18-19 can be lodged in the bottom tube slots 24 to effect interengagement against accidental separation because the wire frames 10 and the tubes 25 can be packed more advantageously and efficiently when separated from each other. These component elements 10-25 are furnished for assembly by the purchaser who also can supply the suspended garment fasteners 29 as independent accessories within the dictates of commercial practice.

The fact that the component hanger elements 10-25 are initially sized to be interfitting without any requirement to effect their assembled retention by tensioning, deforming or straining any portion thereof, the purchaser can perfectly assemble these without any assembling equipment or previous experience or utilization of force which would permanently impair the paper tube 25.

While I have illustrated and described a preferred embodiment of this invention, it must be understood that the invention is capable of considerable variation and modification without departing from the spirit of the invention. I, therefore, do not wish to be limited to the precise details of construction set forth, but desire to avail myself of such variations and modifications as come within the scope of the appended claims.

I claim:

1. In a garment hanger; a supporting hook and a frame of wire having downwardly diverging arms, inwardly curved arm ends on said frame; curved terminals on said arm ends, outwardly extending fingers on said curved terminals defining tube connecting members with said curved terminals, and an open end tubular strut having complementary connecting means therein proximate to the open ends thereof, said inwardly curved arm ends extending for their normal spread axially through the open ends of said tubular strut with said fingers resting on an inside wall of said tubular strut and the curved terminals fitted into said complementary connecting means from within said tubular strut to preclude their separation when said frame ends ex-

tend for their normal spread through the open ends of said tubular strut.

2. In a garment hanger, a supporting hook and a frame of wire having downwardly diverging arms, inwardly curved arm ends on said frame, curved loop terminals on said arm ends, outwardly extending fingers on said curved loop terminals defining tube connecting members with said curved loop terminals, and an open end tubular strut having complementary connecting means therein proximate to the open ends thereof, said inwardly curved arm ends extending for their normal spread axially through the open ends of said tubular strut with said fingers resting on an inside wall of said tubular strut and the curved loop terminals fitted into said complementary connecting means from within said tubular strut to project therethrough as hanger loops and preclude their separation when said frame ends extend for their normal spread through the open ends of said tubular strut.

3. In a garment hanger, a supporting hook and frame of wire having downwardly diverging arms, inwardly curved arm ends on said frame, outwardly curved loop terminals on said arm ends, horizontally extending straight fingers on said curved loop terminals, and an open end tubular strut having slots in the bottom wall proximate to the ends thereof for frictionally receiving said curved arm end terminal loops therethrough with said fingers resting on an inside wall of said tubular strut to preclude their separation when said frame ends extend for their normal spread through the open ends of said tubular strut with said terminal loops and tube slots in operative connection.

4. In a garment hanger, a supporting hook and frame of wire having downwardly diverging arms, inwardly curved arm ends on said frame, curved loop terminals on said arm ends, outwardly extending straight fingers on said curved loop terminals, and an open end tubular strut having a somewhat greater length than the spacing between said inwardly curved arm ends, said tubular strut having end communicating slots therein to reduce the length therebetween to correspond with the spacing of said inwardly curved arm ends that register therewith, said tubular strut having engaging means therein proximate to the ends thereof for receiving said curved arm end terminal loops therethrough with said straight fingers resting on an inside wall of said tubular strut to preclude their separation when said frame ends extend for their normal spread through the open ends of said tubular strut with said terminal loops and tube engaging means in operative connection.

5. In a garment hanger, a supporting hook and frame of wire having downwardly diverging arms, inwardly curved arm ends on said frame, curved loop terminals on said arm ends, horizon-

5 tally extending straight fingers on said curved loop terminals, and an open end tubular strut having a somewhat greater length than the spacing between said inwardly curved arm ends, said tubular strut having end communicating slots therein to reduce the length therebetween to correspond with the spacing of said inwardly curved arm ends that register therewith, said tubular strut having slots in the bottom wall thereof proximate to the ends thereof for receiving said curved arm end loop terminals therethrough with said straight fingers resting on an inside wall of said tubular strut to preclude their separation when said frame ends extend for their normal spread through the open ends of said tubular strut with said terminal loops and tube slots in operative connection.

6. In a garment hanger, a supporting hook and frame of wire having downwardly diverging arms, inwardly curved arm ends on said frame, outwardly curved loop terminals on said arm ends, horizontally extending fingers on said curved loop terminals, and an open end tubular strut having a somewhat greater length than the spacing between said inwardly curved arm ends, said tubular strut having end communicating vertical slots in the upper wall thereof to reduce the length therebetween to correspond with the spacing of said inwardly curved arm ends that register therewith, said tubular strut having slots in the bottom wall thereof proximate to the ends thereof for receiving said curved arm end loop terminals therethrough with said fingers resting on an inside wall of said tubular strut to preclude their separation when said frame ends extend for their normal spread through the open ends of said tubular strut with said terminal loops and tube slots in operative connection.

7. In a garment hanger, a supporting hook and frame of wire having downwardly diverging arms, inwardly curved arm ends on said frame, outwardly curved open loop terminals on said arm ends, horizontally extending straight fingers on said curved loop terminals and an open end tubular strut having a somewhat greater length than the spacing between said inwardly curved arm ends, said tubular strut having end communicating vertical slots therein to reduce the length therebetween to correspond with the spacing of said inwardly curved arm ends that register therewith, said tubular strut having slots in the bottom wall thereof proximate to the ends thereof for frictionally receiving said curved arm end loop terminals therethrough with said fingers resting on an inside wall of said tubular strut to preclude their separation when said frame ends extend for their normal spread through the open ends of said tubular strut with said terminal loops and tube slots in operative connection.
